His Attorney.

UNITED STATES PATENT OFFICE.

STEPHEN D. HARTOG, OF ST. LOUIS, MISSOURI, ASSIGNOR TO S. D. HARTOG MANUFACTURING COMPANY, OF ST. LOUIS, MISSOURI, A CORPORATION.

CHUCKING DEVICE FOR PISTONS.

1,331,918.

Specification of Letters Patent. Patented Feb. 24, 1920.

Application filed March 23, 1918. Serial No. 224,345.

To all whom it may concern:

Be it known that I, STEPHEN D. HARTOG, a citizen of the United States, and residing at St. Louis, Missouri, have invented the new and useful Improvement in Chucking Devices for Pistons, of which the following is a specification.

This invention relates to chucking or work holding devices, and more particularly to devices of this kind adapted for chucking or holding pistons while being machined.

Trunk pistons, such as are used in gas engines, are provided with grooves adapted to receive piston rings. These grooves, however, become worn, especially where eccentric rings are used, and this requires that the grooves be refinished or machined. Such pistons are, however, provided with connecting rods, and in order to permit the piston to be chucked or held in an ordinary work holder, it is necessary to detach the connecting rod from the piston; this, however, involves considerable labor and expense.

One of the objects of this invention, therefore, is to provide a chucking device, which is adapted to receive and hold a piston with its attached connecting rod in place.

Another object is to provide a device of this kind, adapted for pistons and connecting rods of different sizes.

Further objects will appear from the detail description, taken in connection with the accompanying drawing, in which:

Figure 1 is a side elevation of the chucking device or work holder embodying this invention; and

Fig. 2 is a section on the line 2—2, Fig. 1.

Referring to the accompanying drawing, 1 designates a base adapted for attachment to a face plate 2 of a lathe, this base being attached to the face plate by screws 3 passing through enlarged holes in the base, and threaded into the face plate, and in order to center the base on the face plate, this face plate is provided with a centering plug 5, adapted to engage a corresponding hole or aperture in the base.

Formed on or attached to the base are a pair of side members 6 which terminate in a cylindrical support or guide 7, which is threaded to receive a threaded collar or clamping element 8, and which is finished interiorly to provide a guide for a cylindrical extension or guide flange 9 on a piston receiving element 10. The elements 8 and

10 have coöoperating bevel faces 11, so as to center and support the receiving element 10. This receiving element 10 is provided with a series of annular seats 12, each adapted to receive a piston of a certain size, the annular seat being a little larger than the piston, such a piston being shown at 13. The receiving element is further slotted as shown at 14, to receive the connecting rod 15, and this slot 14 is continued through the guide flange 9, so as to permit the receiving element to be placed on and over the connecting rod. In practice, the slot 14 is enlarged at 16 to the width of the largest connecting rod for the largest piston, while the body of the slot 14 need then only be made of a width corresponding to the thickness of the largest connecting rod. The clamping element 8 has an enlarged rib 17, which is knurled on its outer face, and which may also be provided with apertures 18, adapted to be engaged by a suitable wrench.

The side members 6 are provided with pairs of aligned apertures 19 and 20, adapted to receive a plug 21, which, in order to permit its removal or insertion in either pair of aligned apertures, is provided with a knurled head 22. This plug 21 is adapted to engage the crank pin bearing 23 on the connecting rod 15. By shifting the plug to either aligned pair of apertures 20, the device is adapted for connecting rods of different lengths.

In order to chuck a piston and its attached connecting rod, the receiving element 10 is placed over the connecting rod, which can be accomplished when the receiving element is removed from the carrier 1—6—7. The plug 21 is then passed through the center set of apertures 19, and the crank pin bearing. The piston being seated in the receiving element 10, the clamping element 8 is rotated, thereby causing the axial movement of the receiving element 10 to clamp the piston firmly in its seat; the piston can then be machined. After the machining has then been completed, the clamping element is rotated to unclamp the piston, the plug 21 is removed, and by then removing the piston, together with the connecting rod, from its carrier, this piston can be removed from its receiving element through the slot 14.

In practice the adjustment of the clamping element 8 will adapt the device for connecting rods of variant lengths, but where these connecting rods vary considerably, it

is necessary to shift the plug 21 to another pair of apertures in the carrier, and it is for this purpose that a plurality of pairs of apertures are provided. There is, therefore, 5 provided in this device, means for taking care of minor variations in length of connecting rods, and means for taking work of major variations in lengths of connecting rods. In view of the fact that there are 10 many sizes of pistons varying considerably in their diameters, it is necessary to provide various seats for these pistons. In practice, therefore, the receiver 10 is provided with a number of seats, and by providing a number of these receiving elements, 15 all sizes of pistons can be accommodated on a single device, by keeping in stock a number of variant receiving elements. Due to the fact that the adjustment of the receiving element must necessarily be considerable even within the major variations provided for by the different pairs of apertures 19 and 20, it is necessary to provide means for supporting the adjustable receiving element in 20 its different positions. It is for this purpose that the guide flange 9 is provided, which furnishes an extended bearing, and which furnishes a firm support for supporting the receiving element in its different positions 25 in its carrier.

It will, therefore, be seen that the invention accomplishes its objects. The device is one which is adapted to firmly chuck or hold a piston for machining operations 30 without requiring the detachment therefrom of its connecting rod. The device is so constructed that a piston may be readily placed in position and removed, and the operations can, therefore, be performed with 35 great rapidity. Moreover, this device is adapted to pistons of variant sizes. In view of the fact that the self-centered receiving element is centered on the carrier through the coöoperating bevel faces 11 on the receiving element and the clamping elements, 40 and in view of the fact that the carrier is centered on the face plate by the plug 5 coöperating with the hole in the base of the carrier, it is not necessary to waste time in 45 the usual centering operations.

It is obvious that various changes may be made in the details of construction without departing from the spirit of this invention. It is, therefore, to be understood that this 50 invention is not to be limited to the specific construction shown and described.

Having thus described the invention, what is claimed is:

1. A work holder of the class described, 60 comprising, a carrier, means for seating a piston on said carrier, means for retaining the attached connecting rod, and means interposed between said seating and retaining means adapted to clamp the seated piston.

65 2. A work holder of the class described,

comprising, a carrier, means for seating a piston on said carrier, means for retaining the attached connecting rod, and means for moving said seating means adapted to clamp the seated piston.

70

3. A work holder of the class described, comprising, a carrier adapted for attachment to a revolving machine element and for rotation therewith, a receiving element mounted for axial movement on said carrier and provided with a work-receiving seat, a work retaining element mounted on said carrier and adapted to leave said seat unobstructed, and means for causing relative movement of said retaining element and 80 said receiving element to clamp the work.

4. A work holder of the class described, comprising, a carrier adapted for attachment to a revolving machine element and for rotation therewith, a receiving element 85 mounted for axial movement on said carrier and provided with a series of work-receiving seats, a work retaining element and means for moving one of said elements relatively to the other to clamp the work.

5. A work holder of the class described, comprising, a carrier adapted for attachment to a revolving machine element and for rotation therewith, a receiving element 90 guided for movement in said carrier and provided with a work-receiving seat, work-retaining means on said carrier and axially within said seat, and means for moving said element adapted to clamp the work.

6. A work holder of the class described, 100 comprising, a carrier adapted for attachment to a revolving machine element and for rotation therewith, a receiving element guided for movement in said carrier and provided with a work-receiving seat, work 105 retaining means and a shifting element mounted on said carrier and engaging said receiving element, such shifting element and retaining means being adapted to coöperate to secure the work to said carrier for rotation therewith.

7. A work holder of the class described, comprising, a carrier adapted for attachment to a revolving machine element and for rotation therewith, a receiving element 115 having an extension guided in said carrier and provided with a work-receiving seat, work retaining means and a shifting element mounted on said carrier and engaging said receiving element, such shifting element and 120 retaining means being adapted to coöperate to secure the work to said carrier for rotation therewith.

8. A work holder of the class described, comprising, a carrier adapted for attachment to a revolving machine element and for rotation therewith, a receiving element 125 mounted on said carrier and provided with a work-receiving seat, a work retainer mounted on said carrier and adapted to 130

leave said work unobstructed, and means for moving said receiving element relatively to said retainer adapted to clamp the work.

9. A work holder of the class described, comprising, a carrier adapted for attachment to a revolving machine element and for rotation therewith, a receiving element mounted on said carrier, said receiving element guided for movement in said carrier and provided with a work-receiving seat and with a work receiving passage, a work retainer mounted on said carrier, and adapted to engage that part of the work which enters said passage, and means for moving said receiving element adapted to clamp the work.

10. A work holder of the class described, comprising, a carrier, a receiving element mounted on said carrier, said receiving element guided for movement in said carrier and provided with a work-receiving seat and with a work receiving passage, a work retainer mounted for adjustment on said carrier for engaging that part of the work which enters said passage, and means for

moving said receiving element adapted to clamp the work.

11. A work holder for an article having a projecting portion, such holder being provided with a seat for the body of said article and a passage for the projecting portion, adjustable means for engaging and holding against withdrawal of such projecting portion, and means interposed between said engaging means and the seat for producing a seating thrust upon said body portion.

12. A work holder for an article having a projecting portion, such holder having means for attaching the same to a revolving machine element and being provided with a seat for the body of said article and a passage for the projecting portion, and adjustable means for engaging and holding against withdrawal of such projecting portion and producing a seating thrust upon said body portion.

In testimony whereof I affix my signature this 9th day of March, 1918.

STEPHEN D. HARTOG.
